US00D879150S

(12) **United States Design Patent** (10) Patent No.: **US D879,150 S**
Kusano et al. (45) Date of Patent: ** Mar. 24, 2020

(54) **PLAYBACK DEVICE**(71) Applicant: **Sonos, Inc.**, Santa Barbara, CA (US)(72) Inventors: **Mieko Kusano**, Santa Barbara, CA (US); **Ernesto Figueira**, Santa Barbara, CA (US); **Roland Bird**, Eindhoven (NL); **Niels van Hoof**, Eindhoven (NL)(73) Assignee: **Sonos, Inc.**, Santa Barbara, CA (US)(***) Term: **15 Years**(21) Appl. No.: **29/663,323**(22) Filed: **Sep. 13, 2018****Related U.S. Application Data**

(63) Continuation of application No. 29/609,315, filed on Jun. 29, 2017, now Pat. No. Des. 831,646, which is a continuation of application No. 29/554,354, filed on Feb. 10, 2016, now Pat. No. Des. 794,019, which is a continuation of application No. 29/499,300, filed on Aug. 13, 2014, now Pat. No. Des. 754,751.

(57) **CLAIM**

The ornamental design for a playback device, as shown and described.

DESCRIPTION

FIG. 1 is an isometric view of a playback device. FIG. 2 is a front view of the playback device of FIG. 1. FIG. 3 is a rear view of the playback device of FIG. 1. FIG. 4 is a side view of the playback device of FIG. 1. FIG. 5 is another side view of the playback device of FIG. 1. FIG. 6 is a top view of the playback device of FIG. 1; and, FIG. 7 is a bottom view of the playback device of FIG. 1. The features shown in broken lines are for illustrative purposes only and form no part of the claimed design.
